UNITED STATES PATENT OFFICE

LEOPOLD ALMQUIST, OF JERSEY CITY, NEW JERSEY, ASSIGNOR TO AMERICAN CAR AND FOUNDRY COMPANY, OF NEW YORK, N. Y., A CORPORATION OF NEW JERSEY

MINE CAR

Application filed October 5, 1928. Serial No. 310,655.

This invention relates to drop bottom mine cars of the type in which one door automatically operates the latch of a second door to release or lock the second door as the first door is lowered or raised, and it is an object of this invention to provide improved means for hinging and locking doors of mine cars of the type described which will be of simple and rugged construction, of few parts readily applied, reliable in operation and easily maintained in serviceable condition where extensive repair shops are not available.

Other objects and advantages of this invention will be apparent from the following description taken in conjunction with the accompanying drawings in which:

Figure 1 is a broken view showing, partly in side elevation and partly in central longitudinal section, a mine car constructed in accordance with this invention:

Fig. 2 is a partial end elevation looking from the left in Fig. 1;

Fig. 3 is a vertical longitudinal section taken at one of the car axles on line 3—3 of Fig. 4, and showing the door hinging and locking means with the doors in closed position;

Fig. 4 is an elevation of the structure shown in Fig. 3, parts being broken away to show other parts more clearly and the door being shown in open position;

Fig. 5 is a fragmentary view showing in elevation the hinging of the door latch to the car axle;

Fig. 6 is a fragmentary view showing the hinging of the dumping door to the body structure;

Fig. 7 is an end elevation of the door latch shown detached from the car;

Fig. 8 is a view similar to Fig. 3 with the doors in open position;

Fig. 9 is a view similar to Fig. 3 showing the manner in which the door is assembled with the car body; and

Fig. 10 is a view similar to Fig. 3 of a modified construction.

In the drawings, the invention is shown applied to a mine car comprising a body 1 carried upon wheels 2 mounted on axles 3

50 which extend through the body of the car and

are mounted in journal boxes 4 attached to the longitudinal sill members 5 of the car. This car is of the bottom dumping type and the car bottom comprises the doors 6, 8 and 10; the door 6 being mounted upon hinge brackets 12 carried by the end sill 14 and held in closed position by a latch 16 operated by the adjacent door 8. The door 8 is in turn held in closed position by the latch 18 which is identical in construction with the latch 16 and is operated by the adjacent door 10. The door 10 is held in closed position by latches 20 which engage lugs 22 projecting from the free edge of the door; the latches 20 being joined by a connecting bar 24 and pivotally mounted on the end sheet 26 of the car body. One of the latches 20 is provided with an outwardly projecting arm 28 which is operated by engagement with a track ramp, not shown. As the latches 16 and 18 are identical in structure and operation, and as the method of hinging the doors 8 and 10 is identical, a description of but one of each of these parts will be given.

As shown in Figs. 1, 3 and 4, to the sills 5 there are secured hinge brackets 30 provided with openings through which pass the axles 3 and with inwardly projecting ribs 32 the lower portions 34 of which are shaped to form bearings for supporting the doors. To the hinge edge of the doors 8 and 10 are attached hinge straps 36 provided with outwardly projecting trunnions 38 which seat in the bearing surfaces formed by the portions 34 of the ribs 32 and with inwardly projecting lugs 40 mounted eccentrically to the axles of the trunnions 38. The latches 16 and 18 comprise angular plates 42 which extend the full width of the free edges of the doors and are pivotally attached by hinge straps 44 to the axles 3. Secured to the latches at each hinge strap are brackets or braces 45 shaped to conform to the plates 42 and provided with outwardly projecting flanges 46 having laterally projecting ribs 48 of substantially inverted U-shape so as to form slots open at their lower ends. The ribs 48 are engaged by the lugs 40 on the hinge straps 36 when the doors and latches are assembled in the car. The upper portions of the ribs 32 are 104

formed in substantially inverted U-shape as at 50 extending over the axles 3 and of greater projection than the lower portions of the ribs 32, and the portions 50 of the opposite hinge brackets 30 are connected by braces 52 shaped to fit the portions 50 of the ribs 32 and formed with outwardly projecting flange portions 54 and 56 which extend out over the latch and the edge of the door supported thereby and over the hinge edge of the door mounted on the adjacent hinge brackets.

In assembling the latches 16 and 18 and doors 8 and 10 with the body, the latches are first placed upon the axles 3 and then turned to the position shown in Fig. 9; the doors 8 and 10 are then placed in the door position shown at the right in that figure, in which position the lugs 40 are entered into the slots formed by the ribs 48 on the latches 16 and 18, and the trunnions 38 pass between the ends of the bearing portion 34 and portion 50 of the rib 32, this portion of the rib 32 being omitted in order to provide a slot through which the trunnions 38 may be entered. It will be noted, however, that in the extreme position to which the doors 8 and 10 will swing in service, as shown in Fig. 8, that the ribs 48 prevent the trunnions 38 being displaced from the bearing portions 34 of the ribs 32. As an additional precaution, bolts 59 may be inserted in openings in the sills 5 and hinge brackets 30 in position to retain the trunnions 38 in the bearing portions 34.

In the modified construction as shown in Fig. 10, the latch 16 is mounted as is the latch 16 in Figs. 1 and 3, but the rib 32' of the hinge bracket 30' is made continuous and is formed in the lower portion with a circular bearing opening 60 to receive the trunnion 38 of the hinge straps 36. In assembling this construction, it will be necessary to insert the trunnions 38 in the bearing openings 60 before the hinge straps 36 are attached to the doors.

In operation, the latches 20 will be operated by the engagement of the arm 28 against a track ramp (not shown) as the car moves forward or to the right in Fig. 1. Operation of the arm 28 will permit the door 10 to drop, whereupon the lugs 40 through their engagement with the rib 48 will operate the latch 18 withdrawing the latch 18 from beneath the edge of the door 8 as the door 10 is dropped. Releasing the door 8 will permit this door to drop, which operation will in turn operate the latch 16 releasing the door 6 and permitting this door to drop. The doors are returned to raised position by engagement with a track device (not shown) which operates to raise the door 6 first as the car moves along the track. The door 8 is subsequently raised, and raising the door 8 operates the latch 16 to holding position beneath the edge of the door 6. The door 10 is afterwards raised and this in turn op-

erates to place the latch 18 beneath the edge of the door 8. Raising the door 10 will place the lugs 22 in engagement with the latches 20, the latches 20 being returned to their locking position by gravity or by a suitable yielding device, not shown.

What is claimed is:

1. In a drop bottom mine car, a dumping door pivotally mounted on the car, a pivotally mounted latch for holding said door in closed position, said latch having laterally projecting ribs forming open-ended slots thereon, a second drop door, hinges for attaching said second door to said car and lugs carried by said hinges and engaging in said slots to operate said latch.

2. In a drop bottom mine car, a dumping door pivotally mounted on the car, a pivotally mounted latch for engaging the free edge of said door for holding said door in closed position, said latch having laterally projecting ribs forming open-ended slots thereon, a second drop door, hinges for attaching said second door to said car and lugs carried by said hinges and engaging in said slots to operate said latch.

3. In a drop bottom mine car, a bottom dumping door pivotally mounted on the car, a pivotally mounted latch for holding said door in closed position, a second bottom dumping door, hinges for supporting said second door and laterally projecting lugs operating with said hinges and engaging said latch to operate said latch upon operation of said second door.

4. In a drop bottom mine car, a bottom dumping door pivotally mounted on the car, a pivotally mounted latch engaging the free edge of said door to hold said door in closed position, a second bottom dumping door, hinges for mounting said second door, and laterally projecting lugs carried by said hinges and engaging with said latch to operate said latch to release said first door upon opening of said second door.

5. In a drop bottom mine car, a dumping door pivotally mounted on the car, a latch for engaging the free edge of said door for holding said door in closed position, hinges for supporting said latch, blocks carried by said hinges having open-ended slots, a second drop door, hinges for attaching said second door to said car and lugs carried by said hinges and engaging in said slots to operate said latch.

6. In a drop bottom mine car, a dumping door pivotally mounted on the car, a latch for holding said door in closed position, hinges for supporting said latch, blocks carried by said hinges having open-ended slots, a second drop door, hinges for attaching said second door to said car and lugs carried by said hinges and engaging in said slots to operate said latch.

7. In a drop bottom mine car, a dumping door pivotally mounted on the car, a pivotally mounted latch for holding said door in closed position, said latch having open-ended slots therein, a second drop door, hinge straps attached to said second door, outwardly projecting trunnions on said hinge straps for supporting said second door from the car body and inwardly projecting lugs on said straps for engaging in said slots and operating said latch. 10
8. In a drop bottom mine car, a dumping door pivotally mounted on the car, a pivotally mounted latch for holding said door in closed position, said latch having open-ended slots therein, hinge brackets having openings mounted on the car, a second dumping door, hinge straps attached to said second door, trunnions on said hinge straps for engaging with said hinge brackets through said openings and lugs on said hinge straps engaging in the slots on said latch to operate said latch. 15
9. In a drop bottom mine car, a dumping door pivotally mounted on the car, a pivotally mounted latch for holding said door in closed position, a second dumping door, hinge straps attached to said second door, trunnions on said hinge straps, hinge brackets mounted on said car having projecting ribs forming bearing surfaces for supporting said trunnions, said ribs having openings for the insertion of said trunnions, and lugs on said hinge straps engaging said latch to operate said latch. 20
10. In a drop bottom mine car, hinge brackets mounted on said car and having projecting ribs forming bearing surfaces, a dumping door, hinge straps attached to said door and outwardly projecting trunnions on said hinge straps for engaging said bearing surfaces, said ribs having openings for the insertion of said trunnions. 25
11. In a drop bottom mine car, hinge brackets mounted on said car and having projecting ribs forming bearing surfaces, a dumping door, hinge straps attached to said door, outwardly projecting trunnions on said hinge straps for engaging said bearing surfaces, said ribs having openings for the insertion of said trunnions and means connecting the ribs of opposite hinge brackets. 30
12. In a drop bottom mine car, a dumping door, a latch for said door, a second dumping door, hinge straps having outwardly projecting trunnions attached to said second door, hinge brackets on said car having projecting ribs forming bearing surfaces for said trunnions and a guard for said latch connecting the ribs of said hinge brackets. 35
13. In a drop bottom mine car, hinge brackets mounted on said car and having projecting ribs forming bearing surfaces, a dumping door, hinge straps attached to said door, outwardly projecting trunnions on said 40
- hinge straps for engaging said bearing surfaces and means retaining said trunnions in engagement with said bearing surfaces. 45
14. In a drop bottom mine car, hinge brackets mounted on said car and having projecting ribs forming bearing surfaces, a dumping door, hinge straps attached to said door, outwardly projecting trunnions on said hinge straps for engaging said bearing surfaces, said ribs having openings for the insertion of said trunnions and means preventing displacement of said trunnions from said bearing surfaces. 50
15. In a mine car, a drop door pivotally mounted on the car, a latch for said door, said latch having a rib forming an open-ended slot, a second drop door, and a hinge for attaching said second door to the car, said hinge having means operatively engaging in the slot formed by said rib to operate said latch. 55
16. In a mine car, a drop door pivotally mounted on the car, a latch for said door, said latch having a laterally projecting flange of arcuate form, a second drop door, and a hinge for attaching said second door to the car, said hinge having means engaging said flange to operate said latch. 60
17. In a mine car, a drop door pivotally mounted on the car, a latch for said door, said latch having a brace provided with a laterally projecting arcuate flange forming an open-ended slot, a second drop door, and a hinge for attaching said second drop door to the car, said hinge having means engaging in the slot formed by said flange to operate said latch. 65
18. In a mine car, a drop door pivotally mounted on the car, a latch pivotally mounted on the car and engaging the free edge of said door for holding said door in closed position, braces for said latch having laterally projecting arcuate flanges forming open-ended slots, a second drop door, hinge straps attached to said second door, hinge brackets attached to the car and having bearings for supporting said hinge straps and means operating with said hinge straps and engaging in said slots to operate said latch. 70
